E. CARETTE

MOP WRINGER

Original Filed Oct. 22, 1923

FIG. 3

FIG. 1

FIG. 2

FIG. 4

INVENTOR
Ernest Carette,
BY

Ernest Carette
ATTORNEY.

UNITED STATES PATENT OFFICE.

ERNEST CARETTE, OF STE. MARIE, QUEBEC, CANADA.

MOP WRINGER.

Application filed October 22, 1923, Serial No. 670,047. Renewed December 15, 1924.

To all whom it may concern:

Be it known that I, ERNEST CARETTE, a subject of the King of Great Britain, residing at Ste. Marie, in the county of Beauce, Province of Quebec, in the Dominion of Canada, have invented certain new and useful Improvements in Mop Wringers; and I do hereby declare that the following is a true, clear, and exact description of the same.

This invention relates to mop wringers of the class in which the wringer is set upon a pail and the wringing or squeezing is performed by a manually operated device.

The principal object of this invention is to provide a means of automatically setting the device in constant readiness for the wringing operation. Another object is to provide a device of this character, which can be made very economically and yet possess the necessary quality of resistance, while not being cumbersome and heavy, and altogether being easy to operate.

Referring to the accompanying drawings: Figure 1 is a general perspective view of the device according to my invention.

Figure 2 is a side view of same, partly in section, showing its general construction.

Figure 3 is a top view of the same, taken on line 3—3 of Figure 2, and

Figure 4 is also a top view of the same, taken on line 4—4 of Figure 2.

Similar reference characters represent similar parts in all of the views.

A pail or support 1, preferably made of metal and shaped to represent the frustum of a cone, with its larger diameter being the bottom 2 thereof, carries the wringing mechanism on its top 3, and has a foot-board 4, secured at its lower side, for the convenience of the operator, to hold the pail 1 firmly during the wringing operation.

The wringing mechanism consists of a framework made of a circular band 5 resting upon and fastened to the top 3, by means of several brackets 6; another circular band 7 is distanced above and firmly held parallel with band 5, by means of two uprights 8 and 9 set apart from one another. Intermediately disposed of the bands 5 and 7, evenly spaced from one another, are a plurality of semi-circular bars 10, in vertical alignment with bands 5 and 7, and fixed to the uprights 8 and 9. Positioned between

the bars 10 and the bands 5 and 7, and circularly shaped, are prongs 11 extending from the upright 9, to which they are mounted in order to move horizontally, and travelling in that aforesaid position for approximately three-fourths of the entire circle where they are externally held together by a vertical cross-piece 12, to which is attached the end of a belt 13. Another vertical cross-piece 14 is fixed to the other ends of the prongs 11 adjacent the upright 9. Projecting outwardly and fixed to the center of upright 9, on the side of the device, opposite the foot-board 4, and directly in line with the fastened belt 13, is a forked member 15 having its ends 16 vertically disposed in relation to each other, carrying a bushing 17 therebetween, firmly held by a vertical shaft 18, passing through the said ends 16, the said shaft 18 being bent upwardly to form an offset handle 19. The belt 13 is tautly attached to the bushing 17, when the prongs 11 are symmetrically in vertical alignment with the bars 10. A strong flat spring 20 is fixed at about the center of the prong 11 and extends outwardly towards the member 15, where it is also fixed to its forked base 21. Loosely attached at the upper end of the uprights 8 and 9, is a suitable handle 22, for the purpose of handling the entire device.

To operate the said device, it will be obvious that the foot placed upon the foot-board 4 will maintain the device in steady position. The spring 20 will force the prongs 11 into the position shown in Figure 3, the cross-piece 12 abutting against the bars 10 preventing further movement of tension upon the belt 13. By turning the handle 19, which may be arranged to revolve in any direction desired, the belt 13 will enroll itself onto the fixed bushing 17, and the prongs 11 will move outwardly in the direction of the forked member 15, as indicated by the position shown in Figure 4; the former circle, formed by the band 7, in Figure 3, is then reduced into the space 23 shown in Figure 4. A mop or like article being inserted within the device, will be squeezed or wrung, within the said space 23, between the bars 10 and the prongs 11.

After the wringing operation is completed, the operator may let go of the handle 19 and the device will be automatically restored

to its normal position shown in Figure 3, due to the unstraining action of the spring 20.

What I claim as my invention is:

- 5 1. A device of the character described, comprising a supporting element, a plurality of rigid circular bands disposed one above the other in spaced relation, a plurality of movable arcuate prongs disposed 10 between said circular bands, and normally in vertical alignment therewith, means securing said prongs together, means for moving said prongs horizontally relatively to said circular bands, and means to return 15 said prongs to their normal position, substantially as described.
2. A device of the character described, comprising a supporting element, a plurality of rigid circular bands disposed one above 20 the other in spaced relation, a plurality of movable arcuate prongs disposed between said circular bands and normally in vertical alignment therewith, means securing said prongs together, 25 a handle, means connecting at one end said prongs and at its other end connecting one

end of said handle, whereby when said handle is operated said prongs will be moved relatively to said circular bands, and tension means carrying said prongs to their normal 30 position, substantially as described.

3. A device of the character described, comprising a supporting element, a plurality of rigid circular bands disposed one above the other in spaced relation, a plurality of movable arcuate prongs disposed 35 between said circular bands and normally in vertical alignment therewith, a bar securing said prongs together, a handle carrying at one end a fixed bushing, a belt connected 40 at one end to said bushing and at its other end to the bar securing said prongs together, and a tension spring adapted to return said prongs to their normal position, substantially as described. 45

Signed at St. Marys, Beauce, Quebec, Canada, this fourteenth day of July, 1923.

ERNEST CARETTE.
